UNITED STATES PATENT OFFICE.

HAROLD D. CORNWALL, OF LOWVILLE, NEW YORK.

CAPPING DEVICE.

1,169,775.

Specification of Letters Patent.

Patented Feb. 1, 1916.

Application filed October 24, 1914. Serial No. 868,449.

To all whom it may concern:

- Be it known that I, HAROLD D. CORNWALL, a citizen of the United States, and resident of Lowville, in the county of Lewis, in the 5 State of New York, have invented new and useful Improvements in Capping Devices, of which the following, taken in connection with the accompanying drawings, is a full, clear, and exact description.
- 10 This invention relates to certain new and useful improvements in devices for applying caps or closures to bottles, and more particularly to a device for applying the usual bottle closure, in the form of a disk 15 or otherwise, to milk bottles and the like, and is designed particularly for use with the closure shown in reissued Letters Patent of the United States No. 12,529, dated September 4, 1906.
- 20 The primary object of the invention is to provide an exceedingly simple, readily operated, and highly efficient device for applying closures one at a time to bottles or similar receptacles.
- 25 Other objects and uses will appear from the following description, taken in connection with the accompanying drawings, in which—
- Figure 1 is a side elevation of the device. 30 Fig. 2 is a vertical cross section on line 2—2 Fig. 1. Fig. 3 is a horizontal cross section on line 3—3, Fig. 1. Figs. 4 and 5 illustrate slight variations in the details of construction of the temporary cap supporting 35 means. Fig. 6 is a vertical cross section through a multiple capping device for applying caps or closures to a plurality of receptacles simultaneously. Fig. 7 is a horizontal cross section of the multiple capper. 40 The invention comprises a cylindrical body —1—, in use adapted to be vertically disposed, as shown, and having slots —2— and —3— in opposite sides thereof, preferably as shown diametrically disposed, and 45 beginning a short distance from the lower edge of the body —1—, the slot —2— extending to the top of the body —1— and the slot —3— terminating a short distance from the top, for a purpose hereinafter 50 described.
- The lower end of the body —1— is preferably externally threaded for co-action with an internally threaded tubular base —4—, having an inwardly projecting flange —5— and a depending flaring flange or skirt 55 —6—, the portion —6— of sufficient size to inclose the upper edge of a bottle or other similar receptacle —7— as shown.
- A cylindrical sleeve —8— is slidably mounted upon the body —1— and has a 60 circumferentially enlarged portion —9— at its base. The portion —9— is provided with openings —10— and —11— adapted to be simultaneously brought into registration with the slots —2— and —3— for 65 the reception of a handle —12—; and the opening —11— is provided with an eccentric enlargement or slot —13—, and the end of the handle —12— is provided with a projecting pin —14— adapted to slidably 70 pass through the slot and upon a quarter turn of the handle —12— will be brought into registration with a groove or seat —15— in the portion —9—, and for the purpose of retracting the handle and holding 75 the pin —14— in engagement with the seat —15—, a suitable spring —16— is mounted upon the handle —12— and interposed between a weight or hammer —17— and the pin —14— and in operation bears against 80 the inner surface of the body —1— to hold the handle in retracted position, and preferably as shown, a washer —18— is interposed between the spring —16— and the pin —14—, such washer being of sufficient 85 width to prevent its passage through the slot —3—, so that it bears against and has a sliding relation with the inner surface of the body —1—, thus preventing wearing 90 of the spring.
- The weight or hammer is removably or adjustably mounted upon the handle —12— and is adapted to be held in any position of adjustment by a set screw —19—.
- It will be apparent that the sleeve —8— 95 is free to move along the body —1— as limited by the closed lower ends of the slots —2— and —3— and by the closed upper end of the slot —3—, and when caps or bottle closures are to be placed in the body 100 —1—, the handle —12— is pushed inwardly by grasping the operating handle —20— until the pin —14— is disengaged from the slot —15— and the handle —12— is then rotated a quarter turn until the pin 105 —15— registers with the slot —13— when the handle may be withdrawn from the opening —11— and slot —3—, and the sleeve

—8— and the handle —12— may then be slipped off the top of the body —1— to leave the inner portion entirely free for the reception of such caps or closures.

- 5 The diameter of the flange —5— is small enough to ordinarily support the caps and prevent their falling from the body —1—. When the desired number of caps have been stacked in the tubular body, the sleeve —8— is externally telescoped with the body —1—, the handle —12— is passed through the slot —3— and opening —11— and turned to register the pin —14— with the seat —15— and the handle is automatically retracted 10 by the spring —16— to seat the pin —14— in the groove —15— and hold the parts in assembled position.

15 In operation, the flange —6— rests upon the top of the bottle or other receptacle, and 20 by raising and dropping or by pushing down upon the sleeve —8—, the lower-most cap is forced by the supporting flange —5— into the neck of the bottle.

25 The form of cap with which this device is particularly designed for use, comprises two connected disk members —21— and —22—, of different diameters, and spaced apart by an intermediate body —23—, the lower disk —22— is the disk of smaller diameter and 30 is adapted to seat itself in the neck of the bottle, and is of sufficient size to form a closure for the same, and the upper disk —21— is adapted to rest upon the top of the bottle and form a grasping means for removing the closure. With this form of cap, 35 the upper disk —21— is of sufficient diameter to just rest upon the flange —5—, but may be forced past the flange by the application of pressure, as applied through the hammer —17—. It is apparent, however, 40 that although I have illustrated one particular kind of cap which the device is capable of applying to bottles, that I do not desire to limit myself to any particular form, size 45 or shape of cap, as the device is susceptible of use with many and various forms.

50 The flange —5— is merely a means for temporarily supporting the caps within the body —1—, and I do not desire to limit myself to one particular form of flange, or to a continuous flange so long as the device embodies means for temporarily supporting the caps, and in Figs. 4 and 5 are illustrated 55 various manners of forming this supporting means. In Fig. 4, the supporting flange —24— is formed integral with the body —1— by offsetting the lower edge thereof or portions of such edge, and in Fig. 5 a small wire or other suitably shaped member —25— is soldered, brazed, welded or otherwise connected to the inner portion of the body —1— adjacent its lower edge.

60 In Figs. 6 and 7, I have illustrated a capping device for simultaneously applying caps to a plurality of receptacles, and in this 35

particular illustration four simultaneously operated cappers are shown as a basis for the description of a multiple capper which may embody any desired number and arrangement of cap applying devices dependent upon the number of bottles desired to be capped in one operation, and as bottles or receptacles of this character are usually packed and shipped in cases embodying either twelve or twenty bottles, the multiple 70 capper preferably embodies a sufficient number of cap applying devices to apply closures to an entire case of bottles simultaneously. 75

In the construction shown, the base —4— is formed of a single piece of metal, preferably cast in the form shown and having a plurality of inwardly projecting flanges —5— and depending flaring flanges —6— arranged and spaced apart a suitable distance to fit over the upper edge of a corresponding number of bottles for simultaneously applying caps to the same in substantially the manner hereinbefore described with respect to Fig. 2.

80 Each of the bases —4— has a portion which is internally threaded for coaction with its respective tubular body portion —1— in the manner hereinbefore described.

85 A suitable sleeve —8— of sufficient size to inclose the body portions —1— is slidably mounted upon said portions so as to move vertically with reference thereto, and for the purpose of forcing the caps from these body portions and into engagement with the bottles or receptacles and for allowing removal of the sleeve —6— from the body portions to permit insertion of caps or closures as desired, the body portions —1— adjacent the respective operating knobs or handles —20— are slotted vertically upon 90 opposite sides entirely to their tops, as illustrated at —27—, while the body portion farthest from the operating handle —20— are slotted entirely to their top upon one side and the slot terminates some distance 95 from the top upon the other side, it being understood that, as shown, each hammer handle —12— is adapted to support and operate hammers in a row of capping devices, and these hammers —17— are 100 mounted upon and secured to the handle —12— in the manner hereinbefore described with respect to Fig. 2.

105 The end of the handle —12— is mounted in the sleeve —8— and held in operative 110 position by the spring —16— and washer —18— and is removable in the same manner as hereinbefore described with respect to the unitary capping device. As shown, 115 each row of capping devices is provided with a separate hammer handle operating the hammers in all of the devices of that row, and preferably the operating knobs —20— are positioned upon opposite sides of the sleeve —8— and the removable engage- 120

ments of the end of the handles —12— with the sleeve —8— are likewise alternately upon opposite sides of the said sleeve. By raising and dropping, or by pushing down 5 upon the sleeve —8—, a single cap will be forced from each of the body portions —1— and into engagement with the respective receptacles or bottles.

Although I have shown and described one 10 particular form of device and certain arrangements which at present are deemed preferable, I do not limit myself to any particular form, number, size or arrangement 15 of the parts, and it will be apparent that many changes can be made in the details of construction and arrangement without departing from the spirit of this invention as set forth in the appended claims.

What I claim is:

20 1. In a bottle capper, an upright tubular body provided with an elongated longitudinal slot, a grip member movable longitudinally of said tubular body and having a part extending through said slot and adapted to bear upon the upper surface of a cap 25 in said body to force the cap from said body and into engagement with a bottle upon movement of the grip.

20 2. In a bottle capper, an upright tubular body provided with a longitudinal slot and with means for normally supporting caps therein, a grip member externally mounted upon said body and movable longitudinally thereof and having a part extending through 35 said slot adapted to be brought into contact with a cap in said body, a member in connection with said part and adapted to contact with the inner surface of said body, and a spring for holding said member in contact with said body.

30 3. In a multiple bottle capper, a plurality of upright tubular members each provided with a longitudinal slot, a base common to all the members and having a plurality of 45 openings registering with the respective tubular members, means for normally retaining caps in each tube and a grip having a part extending through the slot in each tube and bearing upon the upper surface of 50 the caps in their respective tubes and adapted by movement of the grip to force the caps from said tubes, one by one, into engagement with respective bottles.

4. A bottle capper adapted for applying 55 bottle caps formed of a pair of spaced connected disks of different diameters, comprising a tubular member having a discharge opening adapted to be positioned adjacent the mouth of a bottle, said member adapted 60 to contain said caps with the disk of larger diameter uppermost, and having means for engaging the cap to hold the same within the tube, said engaging means adapted to hold the larger of said disks spaced from the 65 top of the bottle a distance substantially

equal to the distance between said spaced disks, and means for forcing said caps one at a time from said tube to cap bottles.

5. A bottle capper adapted for applying 70 bottle caps formed of a pair of spaced connected disks of different diameters, comprising a tubular member having a discharge opening adapted to be positioned adjacent the mouth of a bottle, said member adapted to contain said caps with the disk of larger 75 diameter uppermost, and having means for engaging the cap to hold the same within the tube, said engaging means adapted to hold the larger of said disks spaced from the top of the bottle a distance substantially 80 equal to the distance between said spaced disks, a grip movable longitudinally of said tubular member, and means actuated by the grip and adapted to bear upon the surface of the caps in said tube for forcing said caps 85 one at a time from said tube to cap bottles.

6. In a bottle capper, an upright tubular body provided with a pair of substantially 90 diametrically disposed longitudinal slots, a grip movable longitudinally of said tubular body, a member extending through said slots and engaged with portions of the grip aligned with said slots, said member adapted to bear upon the upper surface of a cap in 95 said body to force the cap from said body and into engagement with a bottle upon movement of the grip.

7. In a bottle capper, an upright tubular body provided with a pair of substantially 100 diametrically disposed longitudinal slots, one of the same having an open end, a grip movable longitudinally of said tubular body, a member extending through said slots and movably engaged with portions of the grip aligned with said slots and adapted to bear 105 upon the upper surface of a cap in said body to force the cap from said body and into engagement with a bottle upon movement of the grip.

8. In a bottle capper, a tubular body provided with an elongated longitudinal slot open at one end, means for normally retaining caps within the body, a grip member movable longitudinally of said body and having a part extending through said slot 110 and adapted to bear upon the upper surface of a cap in said body to force the cap from said body and into engagement with a bottle upon movement of the grip.

9. In a bottle capper, an upright tubular 115 body having a flange for retaining caps therein and provided with an elongated longitudinal slot, a grip movable longitudinally of said tubular body and having a part extending through said slot and adapted to 120 bear upon the upper surface of a cap in said body to force the cap from said body and into engagement with a bottle upon movement of the grip.

10. In a bottle capper, an upright tubular 130

body provided with a pair of substantially diametrically disposed longitudinal slots, one of the same being closed and the other having an open end at the top, a grip moveable longitudinally of said body, a member extending through said slots and engaged with portions of the grip alined with said slots, said member being movable from engagement with the portion of the grip adjacent the closed slot so that said member

may be withdrawn from the closed slot to allow removal of the grip and member from the tubular body.

In witness whereof I have hereunto set my hand this 12th day of October, 1914.

HAROLD D. CORNWALL.
